UNITED STATES PATENT OFFICE.

WILLIAM JOHN SMITH, OF NEW YORK, N. Y.

TYPE-WRITER ROLLER OR PLATEN.

1,010,698.

Specification of Letters Patent.

Patented Dec. 5, 1911.

Application filed February 8, 1910, Serial No. 542,754. Renewed March 28, 1911. Serial No. 617,499.

To all whom it may concern:

Be it known that I, WILLIAM JOHN SMITH, a citizen of the United States, and a resident of the city and State of New York, have invented certain new and useful Improvements in Type-Writer Rollers or Platens, of which the following is a specification.

My invention relates to the roller or platen of a typewriting machine, upon which is placed the paper upon which the writing is to be produced by the type of the machine, the object of the invention being to produce a roller or platen which shall be strong, durable and otherwise efficient, and at the same time more nearly noiseless than the rollers or platens now in use.

The invention consists in the novel construction, arrangement and combination of elements hereinafter more particularly set forth.

In the accompanying drawings, Figure 1 is a longitudinal vertical section of a typewriter roller or platen constructed according to my invention, Fig. 2 is a transverse vertical section of the same, Fig. 3 is a perspective view of a portion of the invention, which is hereinafter more particularly described, and Fig. 4 is a view of a modification of the invention, as hereinafter described.

In carrying my invention into effect, I provide a tube or sleeve A, of rubber or other suitable material of any desired degree of hardness, which serves as the outer or impact surface of the platen. I also provide an inner tube or sleeve B, of felt or other suitable material of a somewhat soft, yielding or porous nature, adapted to absorb the vibrations produced by the operation of the typewriter, and thereby minimize the noise accompanying the same. Between the outer tube A and the inner tube B is placed a tube or sleeve C, preferably of sheet metal or other similar material.

The tube or sleeve C is provided with a number of perforations or openings D, which are produced by a solid punch or in some other suitable manner so as to not make clean-cut edges, but rather to make rough or ragged depressed edges, forming burs on the inner surface of the tube C, as shown at E.

Inside of the inner tube B, I provide means for holding out in position the comparatively soft and yielding material of the

said tube B, and pressing the same firmly against the tube C and into engagement with the burs on the inner surface thereof. Such holding means may consist of rings of spring sheet-metal, as at F, or split rings of elastic wire, as at G, or any other equivalent means.

Each end of the platen is provided with a disk H, having bearings I, or similar devices, for the purpose of mounting the platen and allowing it to rotate, or the same may be rotatably mounted in any suitable manner.

I do not limit myself to the exact details of construction herein described, nor to the particular materials specified, as it is obvious that other equivalent materials may be employed and that considerable variation in the details of the construction may be permitted, without departing from the spirit and scope of my invention. As one instance of such variation I will mention that the sleeve C may be provided with a series of slits or lengthened perforations, either alone and in substitution for, or associated with, the smaller and approximately circular perforations already described, but always provided with the roughened and inwardly extending edges or burs, so as to efficiently engage with the material of the inner tube B. This modification is shown in Fig. 4.

In the operation of my invention the inner tube B of felt or other suitable soft and vibration-absorbent material is kept pressed up closely against the inner surface of the sleeve C, and the burs E are therefore forced into the soft material B and engage therewith. On this account all vibrations produced in the roller by the impact of the type thereupon or otherwise are effectually damped and absorbed and all undue noise prevented. I have found in practice that a typewriter equipped with a roller or platen constructed according to my invention is far less noisy than a machine provided with the ordinary type of roller or platen, such sound as is made proceeding in such case from parts of the mechanism other than the type and the roller. At the same time, the resistance of the roller to the stroke of the type is amply sufficient to produce a clear and sharp impression upon the paper placed upon the roller, even where a number of sheets of paper, with carbon sheets interposed, are employed, for the purpose of producing carbon copies.

I am aware that it is already known in the art to construct a typewriter roller or platen with an outer layer of comparatively smooth and hard material, such as rubber, 5 forming a type impact surface, and an inner sleeve of softer and less resonant material, and I am also aware that such platens have been constructed with sleeves of perforated sheet-metal, and I do not claim broadly 10 either of the above mentioned features.

What I do claim as new, and desire to secure by Letters Patent, is as follows:

1. A roller or platen for typewriting machines, comprising an outer impact layer or 15 surface, an inner layer of vibration-absorbing and sound-muffling material, and an intermediate layer of material adapted to support and strengthen said outer layer, the said intermediate layer being provided with 20 perforations having inwardly projecting edges forming burs adapted to engage with the material of the said inner layer.
2. A roller or platen for typewriting machines, comprising an outer impact layer or 25 surface, an inner layer of vibration-absorbing and sound-muffling material, an intermediate layer of material adapted to support and strengthen said outer layer, provided with perforations having inwardly projecting 30 edges having burs adapted to engage with the material of the said inner layer, and means for securing the said inner layer in position firmly against the inner surface of the intermediate layer and in engagement with the said burs thereof.

3. A roller or platen for typewriting machines, comprising an outer impact layer or surface, an inner layer of vibration-absorbing and sound-muffling material, an intermediate 35 layer of material adapted to

strengthen said outer layer provided with perforations having inwardly projecting edges forming burs adapted to engage with the material of said inner layer, and elastic means adapted to press said inner layer 45 firmly against said intermediate layer and cause the said burs to engage.

4. In a typewriter roller or platen, the combination with an outer impact layer, of an inner layer of vibration-absorbing 50 and sound-muffling material, and an intermediate layer provided with perforations having inwardly projecting edges or burs engaging with said inner layer.

5. In a typewriter roller or platen, the 55 combination with an outer impact layer, of an inner layer of vibration-absorbing and sound-muffling material, and an intermediate layer provided with perforations or slits having inwardly projecting edges or 60 burs engaging with said inner layer.

6. In a typewriter roller or platen, the combination with an outer impact layer, of an inner layer of vibration-absorbing and sound-muffling material, an intermediate 65 layer provided with perforations having inwardly projecting edges or burs engaging with the said inner layer, and means for holding said inner layer in close proximity to said intermediate layer and in engagement with said burs, said means consisting of a circular spring inside of the inner layer.

In witness whereof I have hereunto signed my name this 7th day of February 1910, in the presence of two subscribing witnesses.

WILLIAM JOHN SMITH.
